ELECTRON DISCHARGE DEVICE

Arthur H. Denzler, Union City, N. J., assignor to
 Bell Telephone Laboratories, Incorporated, New
 York, N. Y., a corporation of New York

Application January 7, 1932, Serial No. 585,204

5 Claims. (Cl. 250—27.5)

This invention relates to electron discharge devices, and more particularly to such devices employing an equipotential, indirectly heated cathode.

5 In discharge devices employing an equipotential cathode which is usually in the form of a metallic cylinder coated with emission material, a heater element which may carry alternating current is provided within the metallic cylinder 10 to convey the heat either by conduction or radiation so that the cathode attains a proper operating temperature for emission of electrons. Usually the heater element is confined in an insulator of quartz or other material which is interposed 15 between the heater and the cathode cylinder.

In this type of construction, considerable time is required for the cathode to attain a uniform and efficient temperature for the emission of electrons to the other electrodes in the device, and in 20 devices of the power type the time element is almost prohibitive to warrant the production of discharge devices employing this cathode assembly.

An object of this invention is to decrease the time element between the application of current 25 to the heater and the attainment of uniform and efficient emission of electrons from the cathode surface.

Another object of this invention relates to the fabrication of a cathode assembly whereby the 30 enclosed elements may be easily denuded of gas.

In one embodiment of this invention, an electron discharge device comprises a plate electrode in the form of a cylinder supported from a stem of the enclosing vessel. An insulating block is 35 supported from the end of the anode remote from the stem, which serves to space one end of the supports for a cylindrical grid and a coaxial equipotential cathode.

The cathode assembly in one aspect of the invention comprises a central supporting rod carrying a sleeve insulating member on which a 40 heater element is wound helically, and a cylindrical metallic cathode sleeve surrounding the heater element and spaced therefrom by end disc members. The end members serve to space the cathode sleeve from the heater so that radiation 45 of heat from the heater is directly to the cathode sleeve which carries an emissive coating on its outer surface.

50 A feature of the invention relates to the support of the cathode sleeve by a leading-in wire extending from the stem, the sleeve being spaced slightly from at least one of the disc members to form a passageway to the interior of the cylinder.

55 This construction permits the complete removal

of occluded gases from the internal elements of the cathode assembly during the manufacture of the device.

The invention and the features thereof will be understood more clearly from the following detailed description with reference to the accompanying drawings in which:

Fig. 1 is a perspective view of an electron discharge device illustrative of one embodiment of this invention with a portion of the enclosing vessel and the anode broken away to show the inner electrodes more clearly;

Fig. 2 is a side view of one end of the electrode assembly of the device shown in Fig. 1 showing in detail the support of the insulator from the anode;

Fig. 3 is a plan view of the electrode assembly of Fig. 2 showing the relation of the electrodes; and

Fig. 4 is an enlarged view in cross-section of the cathode assembly constructed in accordance 20 with this invention and employed in the device shown in Fig. 1.

Referring now to Fig. 1 of the drawings, an electron discharge device illustrative of one embodiment of this invention is shown comprising 25 an enclosing vessel 10 which is secured to an insulating base 11 carrying terminal prongs 12. The vessel 10 is provided with a reentrant stem 13 which terminates in a press 14 from which the cathode and the control electrode or grid are 30 supported. A split metallic collar or band consisting of similar opposed arcuate portions 15 having juxtaposed integral flanges 16 is clamped about the stem 13 by a bolt 17 and nut 18, respectively, only one of each being shown. A plurality of upright members, such as wire rods 19 are attached to the collar and bent toward each other to provide parallel arms 20 which embrace 35 the extensions of a cylindrical anode. The anode may be formed of perforated sheet metal, such as nickel, and comprises opposed semi-cylindrical sections 21 joined by integral flanges 22 which are disposed in face to face relation and are secured, as by welding, between the parallel arms 20 of the rods 19. The perforations in the anode 40 prevent the confinement of heat within the anode, and thereby expedite the cooling of the anode during the operation of the device. As a result, the grid of the device operates at a 45 relatively low temperature and secondary electron emission from the grid is reduced. The flanges 22 are preferably relatively large to increase the radiating surface of the anode and to thereby further expedite the cooling of the anode.

The anode may also be provided with a black 55

coating, such as carbon or an oxide of the metal, to increase heat radiation.

An insulating member 23, such as "lavite", is supported from the anode 21 substantially parallel to the end thereof remote from the stem 13, by a plurality of push-type pins 24 which extend into pockets 25 formed in the flanges 22 of the anode. Each of the pins 24 is provided with a shoulder portion 26 upon which the insulating member 23 rests, and the portion extending through the insulator is turned over at one edge, as shown at 27, to clamp the insulating member 23 upon the shoulders 26. The insulating member 23 is provided with a plurality of relatively large apertures 28 to prevent the confinement of heat adjacent the member and thereby to prevent excessive heating of the insulating member.

A plurality of rigid uprights 29, such as wire rods, are supported from rigid wires 30 embedded in the press 14, and extend within the anode 21 parallel to the longitudinal axis thereof. The free end of each of the uprights 29 extends through oversize bores 31 in the insulating member 23 so that the uprights may expand and contract freely along their lengths with temperature variations during the operation of the device. A helical wire control electrode or grid 32, which may be of carbonized molybdenum, is supported upon the uprights 30 by welding the turns thereof to the uprights, and is concentrically disposed within the anode 21. A leading-in conductor 33 for the grid 32 is sealed in the press 14 and is connected to one of the terminal prongs 12 on the base.

An equipotential heater type cathode assembly, shown in detail in Fig. 4, is disposed concentrically within the anode 21 and grid 32 and comprises a central supporting rod 34, which may be of molybdenum, butt-welded to a bent rigid support 35 of greater diameter than the rod 34 and preferably of nickel, which is secured at its free end to a wire stub 36 embedded in the press 14. An insulating disc or block 37 which may be of magnesium oxide known as magnesia, is seated upon the shoulder formed by the edge of the support 35, and in turn has seated thereupon an insulating sleeve 38, such as of magnesium oxide, which is disposed about the supporting rod 34. Another insulating disc or block 39 encircles the supporting rod 34 and rests against the end of the sleeve 38. A helically wound heater element 40, preferably of tungsten wire, is disposed about and in contact with the insulating sleeve 38 and extends between the insulating discs 37 and 39. An extension 41 of the heater element 40 is threaded through the disc 39 and is secured, as by spot-welding, to the central supporting rod 34 which also serves as a conductor for the heater. An extension 42 of the other end of the heater element 40 is threaded through the insulating disc 37 and is secured to a rigid wire 43 embedded in the press 14. A pair of leading-in conductors 44 are sealed in the press 14 and electrically connect the rigid wires 36 and 43 with certain of the terminal prongs 12 on the base. A cylindrical cathode sleeve 45, which may be of nickel, is coated with barium and strontium oxides 52 which serve as a source of electrons when heated. The cathode sleeve is disposed about the supporting rod 34, and supported from a rigid wire stub 46 embedded in the press by a rigid wire link 47. The wire 46 is electrically associated with one of the terminal prongs 12 on the base

by a leading-in conductor 48 sealed in the press.

As is clearly shown in Fig. 4, the inner diameter of the sleeve 45 is slightly greater than the diameter of the insulating discs 37 and 39. The sleeve 45 is supported longitudinally solely through the wire 47 and is spaced from the heater 40 by the discs 37 and 39. The clearance between the sleeve 45 and the discs 37 and 39 enables the removal of gases from the interior of the sleeve 45 and the denuding of the heater element 40 and insulating sleeve 38 during the evacuation treatment of the device and thereby insures a high vacuum within the enclosing vessel 10. The sleeve 45 is heated substantially by direct radiation of heat from the heater element 40 without the intermediary of an insulating body as in cathodes of this type known heretofore. This enables a very efficient and quick heating of the cathode sleeve 45 to the temperature necessary for uniform and efficient emission of electrons and the time element in heater type cathodes is substantially reduced.

The free end of the central rod 34 extends through a bore in the insulating member 23 and forms a sliding fit with the block, so that the rod 25 may expand and contract freely along its length and the proper position of the cathode with respect to the grid and anode is maintained.

An annular grooved support 49 is mounted on a wire 50 carried by a metallic strip 51 secured to the collar 15 and carries a vaporizable material, such as magnesium. This material is vaporized during the evacuation treatment of the device to fix residual gases within the enclosing vessel 10.

Although a specific embodiment of this invention has been shown and described, it is of course understood that modifications may be made therein without departing from the scope and spirit of this invention as defined in the appended claims.

What is claimed is:

1. An electron emitter for discharge devices comprising a sleeve insulating member, a perforated disc at each end of said member, a heater wire wound on said member, a cylindrical cathode surrounding said member and discs, and a support extending loosely through said member and discs, said heater wire having an end portion extending through said discs, and fastened to said support to prevent movement of said member and discs in one direction, and said support including means for limiting the movement of said member and discs thereon in the opposite direction.

2. An electron emitter for discharge devices comprising a metallic supporting standard having a shoulder thereon, an insulating disc seated on said shoulder, an insulating sleeve encircling said rod and seated upon said disc, another insulating disc seated upon the end of said sleeve, a spiral heater wire around said sleeve, said heater having end portions extending through said discs, one of said end portions being electrically connected to said standard, leading-in conductors secured to said standard and to the other end portion of said heater wire, and a metallic sleeve surrounding said heater element and said discs and having an emissive coating on its outer surface.

3. An electron emitter for discharge devices comprising a central support, an insulating member surrounding said support, a heater element on the surface of said member, spacing insulating blocks surrounding said support at the ends of

5 said member, said heater element engaging said blocks to maintain said member and blocks in position on said support, a cathode sleeve surrounding said support, insulating member, blocks and heater element, and a longitudinal support separate from said central support and spacing blocks maintaining said cathode sleeve in position.

10 4. In an electron discharge device, an enclosing vessel having a stem, a metallic standard extending from said stem, an insulating sleeve on said standard, an insulating disc at each end of said sleeve, said standard including means supporting said sleeve and said discs, a heater wire wound on said sleeve having one end electrically connected to said standard, leading-in conductors embedded in said stem and secured to said standard and to the other end of said heater wire, a cathode sleeve encircling said insulating sleeve and said discs, and a leading-in conductor extending from said stem and supporting said metallic sleeve.

5 5. An electron discharge device comprising an enclosing vessel having a stem, an anode supported from said stem, a push-type insulator carried by said anode, a grid within said anode and supported by said stem and insulator, a metallic support rod extending from said stem and seated in an aperture in said insulator, an insulating sleeve surrounding said rod, insulating discs at opposite ends of said sleeve, a heater wire wound on said sleeve having its ends extending through said discs, one of said ends being electrically connected to said rod, a leading-in conductor extending from said stem and connected to the other end of said heater wire, a cylindrical cathode surrounding said sleeve and discs and spaced therefrom to form a passageway to the interior of said cathode, said cathode being positioned within said anode and grid, and a leading-in conductor extending from said stem and supporting said cathode.
